UNITED STATES PATENT OFFICE

144,111

DESIGN FOR AN AIRPLANE

Walter A. Hite, Palos Verdes Estates, Richard E. Harvuot, Inglewood, and David H. Williams, Los Angeles, Calif., assignors to Interstate Aircraft and Engineering Corp., a corporation of California

Application October 29, 1943, Serial No. 111,534

Term of patent 3½ years

(Cl. D71—1)

To all whom it may concern:

Be it known that we, citizens of the United States, Walter A. Hite, residing at Palos Verdes Estates, in the county of Los Angeles, State of California, Richard E. Harvuot, residing at Inglewood, in the county of Los Angeles, State of California, and David H. Williams, residing at Los Angeles, in the county of Los Angeles, State of California, have invented a new, original, and ornamental Design for an Airplane, of which the following is a specification, reference being had to the accompanying drawing, forming part thereof.

In the drawing:

Fig. 1 is a perspective view of an airplane showing our design;

Fig. 2 is a top plan view of the airplane of Fig. 1;

Fig. 3 is a front elevational view of the airplane;

Fig. 4 is a side elevational view thereof; and

Fig. 5 is an inverted plan view thereof.

We claim:

The ornamental design for an airplane, as shown.

WALTER A. HITE.
RICHARD E. HARVUOT.
DAVID H. WILLIAMS.
